PRODUCTION OF MOTOR FUEL

Eugene C. Hertel, Flossmoor, Ill., assignor to
Sinclair Refining Company, New York, N. Y.,
a corporation of Maine

Application August 5, 1941, Serial No. 405,489

4 Claims. (Cl. 260—683.4)

1

This invention relates to improvements in the production of motor fuel, particularly aviation gasoline, by the alkylation of isobutane with butylenes in the presence of strong sulfuric acid, and in particular, the improvement in such processes by which maximum use of isobutane available in cracked stocks is made while excess butylenes, present in such stocks, are rejected in admixture with normal butane and are available for other purposes.

Processes for the production of motor fuel by alkylation of isobutane with butylenes are known and used. In general, the alkylation is carried out by intimately admixing isobutane, butylenes and strong sulfuric acid for a sufficient period of time for the reaction to proceed, a large excess of isobutane being used. The hydrocarbon is then separated from the acid, and fractionated to separate the alkylate, and also to separate the excess isobutane which is returned to the alkylation reaction zone.

The four carbon atom hydrocarbons from cracked stocks, available in the refinery, contain the three butylenes, isobutane and butane, in somewhat variable proportions, along with minor amounts of other hydrocarbons, and form the usual source of butylenes and a source of part of the isobutane. The quantity of butylenes is usually considerably in excess of the quantity of isobutane, and in many cases, even with isobutane from outside sources, the amount of butylenes in these cracked stocks is in excess of the amount of isobutane available. Accordingly, some of these butylenes must be rejected so that the amount of isobutane and the amount of the butylenes supplied to the alkylation system will balance.

The hydrocarbon separated from the acid after the alkylation reaction contains alkylate, isobutane, normal butane, and other heavier and lighter hydrocarbons in minor proportions. The alkylate and isobutane may be recovered by debutanizing the mixture and treating the bottoms to recover alkylate and deisobutanizing the overhead to recover the isobutane, or may be deisobutanized, with recycling of the overhead and treatment of the bottoms to recover alkylate. It is usually necessary to depropanize the overhead from the deisobutanizer to prevent the propane from building up in the system.

In accordance with the present invention, part or all of the BB feed (the four carbon atom fraction from cracked stocks) is fed to the deisobutanizer in which the excess isobutane is recovered for return to the alkylation unit. This deisobutanizer is operated so that a portion of the butylenes is discharged with the bottoms fraction and a portion goes overhead with the isobutane, advantage being taken of the fact that the straight chain butylenes have boiling points in between those of normal butane and isobutane.

2

The operation is carried out in the known way so that the quantity of butylenes in the overhead is that which is required to maintain the balance between the amount of butylene consumed in the alkylation operation and the available isobutane. Ordinarily, the quantity of butylenes supplied to the reaction zone will be slightly greater than the total amount of isobutane available, because some of the butylenes are consumed by interreaction between themselves to produce hydrocarbons other than alkylate and some are removed as alkyl sulfates in the sulfuric acid purged from the system in accordance with ordinary procedure. All of the BB stock may be charged to the deisobutanizer, or only a part of it may be so charged. Thus a portion, for example, one-half, may be charged to the deisobutanizer while the remainder is charged directly to the alkylation unit or to the depropanizer ordinarily provided just prior to the alkylation unit. The amount of such stock supplied directly to the alkylation unit and that supplied to the deisobutanizer, and the quantity of butylenes rejected in the deisobutanizer will ordinarily be governed by the total quantity of isobutane available, including that in the BB stock and that available from outside sources, such as casinghead.

The invention will be further described in connection with the appended drawing, which illustrates diagrammatically apparatus in which the invention may be practiced.

In the apparatus illustrated, incidental equipment such as pumps, condensers, valves, reflux lines, etc., have not been illustrated.

The BB stock is supplied to the depropanizer 10, the overhead from which is used for any desired purpose. The bottoms are split into two streams, one going directly to the alkylation unit 12 while the other is supplied to the deisobutanizer 14. In the alkylation unit, to which bottoms from the depropanizer 16, derived as hereinafter explained, are also supplied, the hydrocarbons are brought into intimate contact with strong sulfuric acid for a sufficient period of time for the alkylation reaction. The mixture of hydrocarbon and acid removed from the alkylation unit is subjected to stratification in the separator 18, the acid being returned to the alkylation unit and the hydrocarbon introduced into the debutanizer 20. The overhead from the debutanizer, consisting largely of isobutane and normal butane is supplied to the deisobutanizer 14, while the bottoms are charged to a rerun still or otherwise processed to recover the alkylate. Isobutane containing stock from another source such as casinghead, the output of a polymerization plant or the like is processed in the debutanizer 22, and the overhead supplied to the deisobutanizer 14.

The deisobutanizer 14 is operated in the known way, so that substantially all of the isobutane is separated as an overhead product and substan-

tially all of the normal butane and heavy hydrocarbons as a bottoms product, while a portion of the butylenes are included in the overhead and a portion is included in the bottoms, the amount of butylenes discarded in the bottoms being such as to maintain the desired ratio of net input of isobutane to butylenes to the alkylation unit. This ratio should be slightly less than 1 to provide the excess butylenes required to make up for the losses as alkyl sulfate and the losses due to interaction of the olefines. The amount of these losses will vary, depending upon the conditions maintained during the alkylation, but for any given operation are readily determined so that the desired balance can be maintained.

The following tables give typical data for the operation of a plant illustrated in the drawing and described above, operating to produce alkylate from a BB stock and isobutane containing stock from another source.

¹ Includes some propylene or ethylene.

I claim:

1. In the production of motor fuel by the alkylation of isobutane with butylenes in the presence of a catalyst, the steps of bringing an excess of isobutane and the butylenes into intimate contact in the presence of a catalyst, separating the hydrocarbon from the catalyst, and subjecting the hydrocarbon to fractional distillation to recover therefrom the excess isobutane, introducing into the fractionating equipment in which the isobutane is separated a hydrocarbon stock containing isobutane, normal butane and butylenes derived from cracked stocks, operating said fractionating equipment so that a portion of the butylenes having boiling points in between those of normal butane and isobutane is included in the isobutane-containing fraction and a portion in the bottoms fraction, and returning the overhead fraction to the reaction zone, the amount of butylenes in said overhead fraction being regulated so that the total quantity of butylenes supplied to the reaction zone is slightly greater than the total net quantity of isobutane supplied to said reaction zone, on a molar basis.

2. In the production of motor fuel comprising the alkylate resulting from the alkylation of isobutane with butylenes, the steps which comprise separating a four carbon atom fraction containing isobutane, butane and butylenes from cracking stocks, introducing a portion thereof into a deisobutanizer along with a butane and isobutane containing stock removed from the alkylation reaction zone, operating said deisobutanizer to obtain an overhead fraction containing the isobutane and a portion of the butylenes having boiling points in between those of normal butane and isobutane and a bottoms fraction containing the butane and a portion of said butylenes, introducing the overhead along with the remainder of the four carbon atom fraction from the cracking stocks into the alkylation reaction zone, and controlling the proportion of isobutane to butylenes in the reaction zone by regulation of the operation of said deisobutanizer.

3. In the alkylation of isobutane in which a low-boiling mixture of hydrocarbons comprising isobutane, normal butane and low-boiling olefins capable of alkylating said isobutane are reacted to effect alkylation of said isobutane by said olefins, the reaction products are fractionated to separate a fraction comprising unreacted isobutane and substantially free of normal butane and a fraction containing normal butane, and isobutane thus recovered is recycled to said alkylation reaction to maintain an excess of isobutane in the reaction zone, the improvement comprising introducing directly into said fractionating zone a portion of said first-mentioned mixture which contains olefin reactants higher boiling than said isobutane in an amount at least equivalent to the excess of olefin reactants in said mixture over the amount required to alkylate all the said isobutane contained in said mixture whereby the isobutane content of said material thus introduced directly into the fractionating zone is included in the said fraction comprising unreacted isobutane and olefins equivalent in amount to said excess are included in said normal butane fraction, and introducing the remainder of said first-mentioned mixture into said alkylation reaction zone, whereby said excess of isobutane in said reaction zone is maintained.

4. In the production of motor fuel by the alkylation of isobutane with low-boiling olefins in an alkylation reaction zone in which low-boiling

olefins and an excess of isobutane are maintained in intimate contact in the presence of a catalyst and in which the hydrocarbon component of the mixture leaving the reaction zone is thereafter separated from the catalyst and subjected to fractionation to recover therefrom excess isobutane as an overhead fraction which is recirculated to the alkylation reaction zone, and in which at least a portion of the make-up isobutane is supplied in the form of hydrocarbon mixtures containing isobutane and substantial proportions of low-boiling olefins higher boiling than isobutane capable of alkylating said isobutane, the amount of olefins present in said hydrocarbon mixtures exceeding that required to alkylate all of the make-up isobutane available for said alkylation, the improvement compris-

ing supplying to the alkylation reaction zone a first portion of said isobutane and olefin-containing hydrocarbon mixtures, introducing into said fractionating zone a second portion of said isobutane and olefin-containing hydrocarbon mixtures, said second portion having a content of olefins higher boiling than isobutane at least approximately equal to the excess of olefin reactants over the amount required to alkylate the isobutane present in all of the make-up materials, and operating said fractionating zone to exclude said excess olefins from the said overhead isobutane fraction which is recirculated to the fractionating zone, whereby said excess of isobutane in said alkylation reaction zone is maintained.

EUGENE C. HERTHEL.
